UNITED STATES PATENT OFFICE.

ARNO H. PETERSEN, OF MILWAUKEE, WISCONSIN.

DESIGN FOR AN ELECTRIC DRILL.

59,678.

Specification for Design. Patented Nov. 15, 1921.

Application filed June 24, 1921. Serial No. 480,244. Term of patent 7 years.

To all whom it may concern:

Be it known that I, ARNO H. PETERSEN, a citizen of the United States, residing at Milwaukee, in the county of Milwaukee and State of Wisconsin, have invented a new, original, and ornamental Design for an Electric Drill, of which the following is a description, reference being had to the accompanying drawing, forming part thereof.

In the drawing:

Figure 1 is a side view of the electric drill, showing my new design; and

Fig. 2 is an inverted plan view thereof.

I claim:

The ornamental design for an electric drill, as shown.

ARNO H. PETERSEN.

Witnesses:

F. E. DEMPSEY,
Miss R. MEISSNER.
